THOMAS C. YOUNG, OF GLENDALE, CALIFORNIA.

WATER-CIRCULATING MEANS FOR INTERNAL-COMBUSTION ENGINES.

1,110,606.

Specification of Letters Patent. Patented Sept. 15, 1914.

Application filed July 29, 1913. Serial No. 781,759.

To all whom it may concern:

Be it known that I, THOMAS C. YOUNG, a citizen of the United States, residing at Glendale, in the county of Los Angeles, State of California, have invented a new and useful Improvement in Water-Circulating Means for Internal-Combustion Engines, of which the following is a specification.

- 10 10 This invention relates to improvements in the water circulating system used in connection with gasoline engines, such system including a water jacket for the engine and a radiator connected to the water jacket.
- 15 15 The main object of the present invention is to conserve the water in such a system, so that when the apparatus has once been filled with water it will remain full for an indefinite time.
- 20 20 In connection with the radiator above referred to an overflow pipe is generally provided, which is open to the outer air, and through which water or steam escapes when the water in the radiator is boiling. This results in loss of water from the apparatus and my invention provides for retaining this water in such manner that it is drawn back into the radiator when it cools.

Another object of my invention is to prevent access of air to the radiator, thereby preventing rusting of the radiator walls. In the operation of a radiator having an open overflow, air is drawn into the radiator through this overflow whenever the radiator cools, resulting in serious damage to the radiator by rusting, and my invention avoids this objectionable action by sealing the water circulating system from direct contact with the air.

- 40 40 Other objects of my invention will appear hereinafter.

The accompanying drawings illustrate an embodiment of my invention and referring thereto: Figure 1 is a vertical section of an automobile provided with my invention. Fig. 2 is a plan view of the water circulating system and the overflow receiver therefor.

The invention is shown as applied in connection with an automobile, but is capable of general application to internal combustion engines of the water cooled type.

- 50 50 1 designates the body or frame on which the engine 2 and radiator 3 are mounted. Engine 2 is provided with the usual water jacket 2' having water circulating connections 4 and 5 with the radiator, the arrange-
- 55 55

ment shown being of the thermosiphon type, wherein the circulation is effected automatically, without the use of a pump. The radiator is provided at its top with the usual filler cap 6, and an exhaust or overflow pipe 8 opens at its upper end into the space at the top of the radiator, for example, directly beneath the cap 6, said pipe extending downwardly and through the radiator wall. To this pipe is connected, by a union 9, a pipe 10 leading to a receiver or tank 11, a sealing tube 12 being connected to the pipe 10 by a union 13 and extending down into tank or receiver 11 and opening at its lower end into said tank, near the bottom thereof. Said receiver and the pipe connecting it with the radiator are lower than the overflow outlet from the radiator into said pipe, so that water boiling over at said outlet will flow by gravity to the receiver. A vent pipe 14 communicates with the upper part of tank or receiver 11 and extends downwardly outside the tank. Tank 11 is provided with a filling opening 80 normally closed by a screw plug 15.

The operation is as follows: The water jacket 2', radiator 3 and receiver or tank 11 are charged with water, and in the operation of the engine the water in the water jacket becomes heated and flows automatically to the radiator and from the radiator back to the water jacket. Whenever the water in the radiator becomes hot enough to boil, steam and water escape through the exhaust or overflow pipe 8, and are conducted by pipes 10 and 12 to the lower part of tank or receiver 11. Any steam so entering the tank 11 is condensed as it rises through the cold water in said tank. Thus the body of water in the tank or receiver 11 acts as a condensing means for the steam escaping from the radiator, when the latter becomes hot, and it also acts as a seal for preventing air from passing back through pipe 10 to the radiator when the latter cools. On cooling of the radiator any steam in the upper part of the radiator becomes condensed and a vacuum is produced in the radiator at the top of the overflow pipe, with the result that water is drawn from receiver or tank 11 back into the radiator, by reason of the deficiency of pressure in the radiator as compared with that in the tank 11. Thus the apparatus is maintained in charged condition, and no water is lost to the system as a whole.

The pipe 14 maintains connection from the atmosphere to the interior of tank 11, so that when a vacuum is produced in the radiator, the atmospheric pressure in the tank 11 forces the water back into the radiator, and on the other hand, it acts as a safety vent, to permit the escape of any steam which might be generated in the tank 11 by reason of excessive heating of the radiator.

10. What I claim is:

1. The combination with the water jacket of an internal combustion engine, and a radiator connected to said water jacket, provided with a filler cap and with an overflow outlet below said cap, of a receiver for containing a body of water, said receiver being open to communication with the atmosphere, and an overflow pipe leading from said overflow outlet of said radiator and communicating with the receiver below the level of the water therein, said overflow pipe and receiver being lower than the overflow outlet from the radiator, to allow flow of water from said outlet to the receiver by gravity, to receive the overflow and steam from the radiator when the water therein boils, and to feed the overflow and condensed steam back to the radiator when it cools.

2. The combination with the water jacket of an internal combustion engine, and a ra-

diator connected to said water jacket, provided with a filler cap and with an overflow outlet below said cap, of a receiver for containing a body of water, and an overflow pipe leading from said overflow outlet of said radiator, and opening into the body of water in the receiver, said receiver being provided with a vent at its upper portion, and said overflow pipe and receiver being lower than the outlet from the radiator, to allow flow of water from the said outlet to the receiver by gravity.

3. The combination with the water circulating system for an internal combustion engine, of an overflow pipe therefor, and a receiver open to atmospheric pressure and connected to said overflow pipe to receive the discharge from said pipe when the water in the system boils and to retain the discharge and feed it back into the system when the latter cools, said overflow pipe and receiver being lower than the overflow outlet from the water circulating system to said overflow pipe, to allow flow of water from said overflow outlet to the receiver by gravity.
